Atty's:

UNITED STATES PATENT OFFICE.

WALTER VAIL JOHNSTON, OF MILWAUKEE, WISCONSIN.

DESIGN FOR A GLASS JAR.

Application filed December 24, 1926. Serial No. 20,142. Term of patent 7 years.

To all whom it may concern:

Be it known that WALTER VAIL JOHNSTON, a citizen of the United States, residing at 501 Wahl Ave., Milwaukee, in the county of Milwaukee and State of Wisconsin, has invented a new, original, and ornamental Design for Glass Jars, as shown in the accompanying drawing and described in the following specification.

Figure 1 illustrates a front elevational view of the design for a glass jar.

Figure 2 illustrates a side elevational view of the design.

Figure 3 represents a top plan view of the design for a glass jar.

I claim:

The ornamental design for a glass jar as shown.

WALTER VAIL JOHNSTON.
